ALFRED HEALD, OF PHILADELPHIA, PENNSYLVANIA, ASSIGNOR TO
McCALLUM, CREASE & SLOAN, OF SAME PLACE.

Design No. 4,881, dated May 9, 1871.

DESIGN FOR A CARPET-PATTERN.

The Schedule referred to in these Letters Patent and making part of the same.

I, ALFRED HEALD, of Philadelphia, county of Philadelphia, State of Pennsylvania, have invented or produced a Design for a Carpet-Pattern, of which the following is a specification.

The figure in the accompanying drawings represents sufficient of a carpet-pattern to illustrate the design, which consists, mainly, of members A and B, and of the intervening space C, the latter itself appearing in the drawings to form a large four-armed figure.

The members A and B are of the same size and shape, and differ only in their interior ornamentation.

Each member A has in the center a diagonal bar, *a*, and at each end of the latter a small figure, *b*, there being, also, diagonal rows of small spots, *c*, all of the character represented.

The interior of each member B is occupied by foliated ornaments *d*, and by short diagonal bars *e* combined with the same, as shown.

The space C, which should be of a shade differing from that of the members A and B, is occupied by a central ornament, *f*, and by four square or diamond-shaped figures *g*, surrounding the said ornament, the

latter, as well as the said figures, being of a character too clearly shown in the drawings to require minute description.

Irrespective of the colors employed,

I claim—

1. The design for the members A, substantially as shown and described.
2. The design for the members B, substantially as described and represented.
3. The design for the space C between the members A and B, with its ornaments *f* and *g*.
4. The design for the whole pattern, including the members A and B and the ornamented space C.

In testimony whereof I have signed my name to this specification in the presence of two subscribing witnesses.

ALFRED HEALD.
